UNITED STATES PATENT OFFICE.

MILES J. LAWLER, OF PARNELL, IOWA.

WASHING-MACHINE.

SPECIFICATION forming part of Letters Patent No. 736,410, dated August 18, 1903.

Application filed September 12, 1902. Serial No. 123,093. (No model.)

To all whom it may concern:

Be it known that I, MILES J. LAWLER, a citizen of the United States, residing at Parnell, in the county of Iowa and State of Iowa, have invented certain new and useful Improvements in Washing-Machines; and I do hereby declare the following to be a full, clear, and exact description of the invention, such as will enable others skilled in the art to which it appertains to make and use the same.

This invention relates to washing-machines; and it consists of the novel construction and combination of the parts hereinafter fully described and claimed.

15 In the drawings, Figure 1 is a vertical section through the washing-machine. Fig. 2 is a plan view of the washing-machine. Fig. 3 is a plan view of the clothes-agitator. Fig. 4 is a side-view of one of the toothed segments. 20 Fig. 5 is a detail sectional view of the agitator and its driving-wheel. Fig. 6 is a detail view of the post K and bearing k.

A is the washtub, supported on legs a'. This tub is of any approved construction, and 25 its sides and bottom are plain or corrugated, as may be required. The tub is provided with a lid B, which is hinged to it in any approved manner.

C is the agitator-shaft, which is journaled 30 in a plate c, secured to the top of the tub. The plate c has openings c' in it, and D represents antifriction-rollers arranged in the openings c' and journaled on pins d, inserted in the said plate.

35 E is a sleeve which is secured on the lower part of the shaft C by a pin e and provided with a flange f at its lower part and longitudinal projecting ribs f' on its sides.

F is the agitator, which consists of a plate 40 provided with arms g for engaging with the clothes. The agitator fits loosely over the sleeve E and normally rests on its flange f below the pin e, and it is provided with notches which engage loosely with the ribs f'. In this 45 manner the agitator is constrained to revolve with the shaft C, but is free to tip or tilt to a limited extent in any direction.

G is a toothed wheel provided with a sleeve h, having a flange h' at its top. The wheel 50 and sleeve are rigidly secured on the agitator-shaft C, and the wheel runs on the antifriction-rollers D.

H represents arms arranged equidistant from each other between the flange h' and the body of the toothed wheel G. Weights 55 i are secured on these arms and may be either fixed or removable. When removable, lighter or heavier weights may be substituted for them. These weights balance each other, being arranged at equal distances apart. 60

I is a screw-threaded cap which is adjustable upon the screw-threaded upper end portion of the shaft C. This cap has a conical bearing j, which engages with a corresponding bearing in an arm or bracket J, which is 65 secured to the lid of the tub, so that the shaft C is prevented from rising.

K is a circular post or pin which is secured to the lid of the tub parallel with the shaft C. A bearing k is formed at the top of the post 70 K and is provided with a removable cap k'.

L is a bearing secured to the lid of the tub a short distance from the bearing k.

M is the operating-shaft, which is journaled in the bearings k and L, and m is a fly-wheel 75 secured on the shaft M and provided with an operating-handle m'.

O and P are two toothed segments secured upon the shaft M and arranged upon opposite sides of the bearing k. The teeth of 80 each segment are arranged opposite the toothless portion of the other segment, each segment having teeth on one half only of its periphery.

R is a toothed wheel which is journaled on 85 the post or pin K and which is engaged by the toothed wheels O and P alternately as the shaft M is revolved.

S is a toothed wheel which is secured to the wheel R and which also is journaled on 90 the post or shaft K and which gears into the toothed wheel G on the agitator-shaft. The wheel S is preferably smaller in diameter than the wheel G.

When the operating-shaft is revolved continuously in one direction, the agitator is oscillated inside the tub and washes the clothes placed in the tub in a very effective manner. 95

The weights are made removable in any approved manner—as, for instance, by having slots like the weights of a weighing-machine. These weights are slid upon the inclined arms H to different distances from the center of the shaft, so as to balance the wheel 100.

G in its normal position on the rollers. The weights also counteract the upward pressure of the clothes in the tub. When the machine is in operation, the clothes frequently collect under the agitator, and if the weights were not used or if they were too light the agitator when bearing against the pin e would force the sleeve E upward against the lid of the tub or would press the bearing j hard against the bearing in the end of the bracket J, and thereby make the machine very hard to turn.

I do not herein claim the driving-gear shown and described in this application, as the same is fully described and is claimed in a separate application for same, filed on June 6, 1903, Serial No. 160,336.

What I claim is—

1. The combination, with a tub provided with a lid, and an agitator-shaft journaled in the lid; of an agitator carried by the said shaft, a driving-wheel secured on the said shaft and provided with arms, weights on the said arms which operate to counteract the upward pressure of the clothes in the tub, and driving mechanism for operating the said wheel, substantially as set forth.

2. The combination, with a tub provided with a lid, and an agitator-shaft journaled in the lid; of a sleeve secured on the lower part 30 of the said shaft and provided with stops, an agitator revolving with the said sleeve and movable vertically between the said stops, a driving-wheel secured on the upper part of the said shaft, and removable weights carried by the said wheel and operating to counteract the upward pressure of the clothes in the tub, substantially as set forth.

3. The combination, with a tub provided with a lid, and an agitator-shaft journaled in 40 the lid; of an agitator carried by the lower part of the said shaft, a toothed wheel secured on the upper part of the said shaft and provided with a sleeve on its upper side having a flange and equidistant bars extending 45 between the said flange and the body of the said wheel, and weights on the said bars, substantially as set forth.

In testimony whereof I affix my signature in presence of two witnesses.

MILES J. LAWLER.
